US0D1055031S

(12) **United States Design Patent** (10) Patent No.: **US D1,055,031 S**
(45) Date of Patent: ** Dec. 24, 2024

(54) **EARPHONE CASE AND EARPHONES**

(71) Applicant: **Yun Deng**, Guangdong Province (CN)

(72) Inventor: **Yun Deng**, Guangdong Province (CN)

(**) Term: **15 Years**

(21) Appl. No.: **29/887,929**

(22) Filed: **Mar. 27, 2023**

(51) LOC (14) Cl. **14-01**

(52) U.S. Cl.

USPC **D14/223; D3/274**

(57) **CLAIM**

The ornamental design for an earphone case and earphones as shown and described.

DESCRIPTION

FIG. 1 is a perspective view of an earphone case and earphones showing the new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a perspective view thereof;

FIG. 9 is a second perspective view thereof;

FIG. 10 is a third perspective view thereof;

FIG. 11 is a fourth perspective view thereof;

FIG. 12 is a front perspective view of the left earphone thereof, shown separately for clarity of illustration;

FIG. 13 is a rear elevational view thereof;

FIG. 14 is a left side view thereof;

FIG. 15 is a right side view thereof;

FIG. 16 is a top plan view thereof;

FIG. 17 is a bottom plan view thereof;

FIG. 18 is a perspective view thereof;

FIG. 19 is a front perspective view of the right earphone thereof, shown separately for clarity of illustration;

FIG. 20 is a rear elevational view thereof;

FIG. 21 is a left side view thereof;

FIG. 22 is a right side view thereof;

FIG. 23 is a top plan view thereof;

FIG. 24 is a bottom plan view thereof; and,

FIG. 25 is a perspective view thereof.

The broken lines depict portions of the earphone case and earphones that form no part of the claimed design.
